FILLER FOR PIPE-JOINTS.

1,248,361.

Specification of Letters Patent. Patented Nov. 27, 1917.

Application filed June 15, 1916. Serial No. 103,904.

To all whom it may concern:

Be it known that I, JAMES R. MCWANE, a citizen of the United States, residing at Birmingham, in the county of Jefferson and 5 State of Alabama, have invented a new and useful Filler for Pipe-Joints, of which the following is a specification.

This invention has reference to fillers for pipe joints.

10 In bell and spigot lead-packed joints it is necessary to first pack jute or other like material in the bottom of the packing space to center the pipe and prevent the lead from running into the pipe. The space required 15 for this jute packing is larger than is necessary for the lead required for packing purposes only, but the space cannot be reduced because of the difficulty of driving the jute packing into a smaller space than is now 20 used. The result is that there is a large dead space that must be filled with either lead or jute.

When the dead space is filled with jute there is formed a cushion which is not desirable in calking the lead. Good practice 25 therefore, demands that the dead space be filled with lead. The lead, from the apex of the lead ring or groove to the jute, constitutes only an expensive filler, not being effective in forming the joint.

The object of the invention is to substitute for the unnecessary lead a cheaper filler constituting at the same time an effective device for automatically tightening the joint when 30 disturbed after installation and therefore there is effected a material reduction in the cost of joint material while the efficiency of the joint is materially increased.

In accordance with the present invention, 40 the ordinary commercial type of bell and spigot cast iron pipe may be employed to be initially packed, close to the shoulder of the bell, where receiving the spigot end of the pipe, with jute, and against such jute packing there is applied a series of blocks formed 45 of metal or other material and preferably spaced and joined into a ring by a flexible connector, the continuity of the ring being broken at one or more points for convenience of application of the ring. Then more jute is added, and finally lead is applied in the usual way, completing the joint, but because of the presence of the ring the quantity of lead needed is materially decreased. 50 The blocks are preferably in the form of double taper wedges with intervening flats

or plateaus between the wedge ends, and, moreover, the sides of the blocks may be beveled to permit conformity of the united blocks into relatively close contact with each other and with the pipe when applied. The shape of the blocks is such as to allow for slight imperfections in the bells or spigots and for deflections in the pipe line.

The invention will be best understood 65 from a consideration of the following detailed description, taken in connection with the accompanying drawings forming part of this specification, with the further understanding that while the drawings show a 70 practical form of the invention, the latter is not confined to any strict conformity with the showing of the drawings, but may be changed and modified so long as such changes and modifications come within the 75 scope of the appended claims.

In the drawings:—

Figure 1 is a view of a string of connected wedge blocks laid out flat, the view being taken from what constitutes the inner face 80 when such string of blocks is applied in the form of a ring to the pipe joint.

Fig. 2 is a view similar to Fig. 1 but of the opposite face.

Fig. 3 is a longitudinal central section of 85 the structure of Fig. 1, the section being taken along the line of the connecting wire.

Fig. 4 is a cross-section of one of the wedge blocks of Fig. 1 showing the wire in place.

Fig. 5 is a longitudinal diametric section 90 of a completed joint.

Fig. 6 is a section on the line 6—6 of Fig. 5.

Referring to the drawings there is shown 95 the bell end 1 and spigot end 2 of a commercial form of cast iron pipe. The bell end 1 has the usual internal bottoming shoulder 3 and circumferential shoulders 4 and 4^a within the bell near the mouth thereof. The 100 spigot end 2 is provided with the usual external terminal bead 5.

There is also provided a string of wedge blocks 6. Each block in the showing of the drawing is of rectangular outline with the 105 ends tapering to form wedge surfaces 7 and these wedge surfaces are spaced apart by a plateau 8 on the same face of the block as the wedges 7. The side edges of each block are beveled, as indicated at 9, and the several blocks are cast upon a wire 10 in sufficiently close edge to edge relation so that

the series of blocks may be formed into a ring of approximately circular form with the sides in close, though not necessarily touching relation. The wire 10 is fast to 5 the blocks midway of the length of the latter, the blocks being ordinarily somewhat longer than wide, so that the blocks when formed into a ring may be rocked on the wire connector sufficiently to form the ring 10 into frusto-conical contour with the wedge portions of one edge of the ring of less diameter than the wedge portions of the other edge of the ring. In this manner the ring of blocks or wedges fits against the interior 15 of the bell adjacent to the shoulder 4 with the more expanded wedge edge presented toward the mouth of the bell, while the other wedge edge of the ring is close to or in contact with the spigot end of the pipe in- 20 troduced into the bell.

In assembling the parts the spigot 2 is introduced into the bell 1 and then a small quantity 11 of jute is first driven up in the usual manner, after which the ring of 25 blocks 6 constituting a filler is inserted, and this is followed by more jute 11^a, which forces that edge of the filler ring toward the mouth of the bell over into the customary lead receiving groove of which the 30 shoulder 4 forms one wall, the outer or rear faces of the blocks 6 bearing against the other portion of the wall of the lead receiving groove.

Finally lead is poured into the bell and 35 calked as in the ordinary practice, the lead anchoring against the shoulder 4, and, pressing on the corresponding wedge ends 7 of the various blocks 6 of the filler ring, forces these blocks against the remaining wall 4^a 40 of the lead-receiving groove in the bell.

The filler provides a backing or foundation against which to calk the lead, making it possible to drive the lead into the lead-receiving groove with much less labor than 45 heretofore.

When pressure comes on to the lead either from the ordinary internal pressure within the pipe or from settling of the pipe joint and consequent leverage on the lead tending 50 to force the latter out of the joint, the face of the wedge forces the lead over against the pipe and up against the lead ring or groove, thereby making the joint tighter.

The stronger the pressure exerted from the 55 inside to force the lead out, the tighter the joint becomes, so that the filler actually serves as a tightening wedge filler.

It has been proven both by theory and practice that a cast iron pipe must have 60 two opposing factors, that is, rigidity and flexibility. It follows then that the perfect joint is the one in which these two opposing factors meet at the proper point. Otherwise the joint becomes either too rigid or 65 too flexible. The perfect joint must have

enough rigidity to resist deflection up to a certain point and then yield. It must have enough flexibility to permit deflection when such point is reached, but without leaking.

In tests made upon a four inch pipe joint 70 containing the present invention, the pipe at the joint was deflected seven and one-half inches from alinement and subjected to an internal hydrostatic pressure of three hundred pounds, without any indication of 75 leakage, even though the lead was squeezed out of the joint at what then constituted the bottom portion thereof to an extent of one-eighth of an inch. Such test was only one of a long series of tests, but the results 80 were all similar.

With the joint of the present invention there is a saving of about fifty per cent. of lead. There is obtained a fuller expansion of the lead into the lead ring or groove with 85 less labor than heretofore. The rigidity of the joint is increased while still retaining sufficient flexibility. Moreover, the joint becomes actually and positively tighter under pressure or deflection than has heretofore 90 been the case with ordinary cast iron pipe.

The joint is also cheaper in installation than is the case with the ordinary lead joint. Taking a four inch joint as an example with the filler costing a customer twenty cents, 95 the saving in lead amounts to approximately thirty-four cents with lead at nine cents a pound, so that the net saving is fourteen cents per joint, or one dollar a ton of standard water pipe, with the further advantage 100 of obtaining a better joint than is obtainable with ordinary cast iron pipe by the ordinary mode of forming the joint.

While the invention has been described with particular reference to cast-iron pipe 105 it is to be understood that it may be used with steel or wrought-iron pipe. Also the blocks, while preferably formed and joined as described, may be otherwise formed and otherwise joined, or not joined at all, and 110 may be cast iron or other material.

Furthermore, while the packing material has been described as lead, other packing materials may be substituted therefor.

What is claimed is:—

1. Filling means for the joints of bell and spigot pipe, comprising a series of relatively thin blocks with the opposite faces substantially flat, and said blocks being arranged edge to edge and introducible into the bell 120 end of a pipe as a circular series after the spigot is applied, and constituting a backing for sealing material occupying the mouth portion of the bell about the spigot.

2. A filler for joints of bell and spigot 125 pipe, comprising a series of flexibly connected relatively thin blocks with opposite faces substantially flat and arranged edge to edge, said series of blocks being introducible in the form of a circular series into the packing 130

space in the bell to constitute a backing for sealing material occupying the mouth portion of the bell.

3. A filler for joints of bell and spigot pipe, comprising a series of relatively thin wedge blocks with substantially flat faces on opposite sides and arranged edge to edge, said series of blocks being introducible in a substantially circular series into the packing space in the bell to constitute a backing for sealing material introduced into the mouth of the bell.

4. A filler for joints of bell and spigot pipe, comprising a flexibly connected series of relatively thin wedge blocks having opposite faces substantially flat, the blocks being arranged edge to edge and introducible in the form of a circular series into the packing space in the bell to constitute a backing for sealing material located in the mouth portion of the bell.

5. A filler for joints of bell and spigot pipe, comprising a series of blocks arranged edge to edge to be introduced into the bell portion of the joint as a circular series and the edges of the blocks other than those edges adjacent to neighboring blocks being formed into wedges directed toward the base of the bell and toward the mouth thereof when in place, whereby those wedge edges toward the mouth of the bell constitute a backing for sealing material introduced into the mouth of the bell.

6. A filler for joints of bell and spigot pipe, comprising a series of blocks formed into wedges at the opposite ends and beveled at the edges toward the same face to constitute a filling ring when introduced into the bell end of a pipe already containing the spigot end of the next pipe in order.

7. A filler for the joints of bell and spigot pipes, comprising a series of flexibly connected blocks arranged edge to edge and sufficient in number to form a ring within the bell end of the pipe about the spigot introduced thereinto, the blocks having their opposite ends thinned to constitute wedges and their edges beveled toward the same face to conform to the circular shape of the bell and spigot.

8. A filler for joints of bell and spigot pipe, comprising a series of metal blocks

each with opposite ends of wedge shape and opposite edges beveled toward the same face, and a flexible wire joining the blocks and extending lengthwise of the series intermediate between the wedge ends on the face of the block remote from that containing the wedge ends.

9. A filler for joints of bell and spigot pipe, comprising a series of metal blocks each with opposite ends of wedge shape and the sides beveled, and a flexible wire joining the blocks and extending lengthwise of the series intermediate between the wedge ends on the face of the block remote from that containing the wedge ends, said blocks being cast about the wire to permanently unite the blocks and wire together.

10. A filler for joints of bell and spigot pipe, comprising a series of wedge blocks introducible into the packing space between the mouth end and the bottom of the bell and of a thickness sufficiently less than the width of the packing space to rock therein and force the packing material toward the mouth end of the bell and compress it between the shoulder of the packing groove and the introduced pipe when the pipe joint settles and gets out of its installed position.

11. A filler for joints of bell and spigot pipe, comprising a flexibly joined series of wedge blocks arranged in edge to edge order and shaped to assume in the joint the form of a conical ring to constitute a backing against which lead introduced into the bell part of the joint may be calked.

12. A filler for the joints of bell and spigot pipe, comprising a series of blocks of greater width than thickness and arranged in edge to edge relation with the blocks joined together and movable when the series of blocks is lodged in the joint into the form of a conical ring to constitute a resistant backing or anvil against which to calk lead introduced into the joint.

In testimony, that I claim the foregoing as my own, I have hereto affixed my signature in the presence of two witnesses.
